UNITED STATES PATENT OFFICE.

JAMES J. GIBNEY, OF MINNEAPOLIS, MINNESOTA.

DISHWASHING MACHINE.

Application filed August 29, 1924. Serial No. 734,907.

My invention relates to dish washing machines and involves various novel features of construction whereby the operation of the machine is improved and the manufacture thereof at comparatively low cost is facilitated. Generally stated, the invention consists of the novel devices and combinations of devices hereinafter described and defined in the claims.

10 In the accompanying drawings, which illustrate an embodiment of my invention, like characters indicate like parts throughout the several views.

Referring to the drawings:

15 Fig. 1 is a vertical section taken through the machine approximately on the line 1—1 of Fig. 2, some portions being shown in full;

Fig. 2 is a horizontal section on the line 2—2 of Fig. 1;

20 Fig. 3 is a fragmentary horizontal section taken approximately on the line 3—3 of Fig. 1;

Fig. 4 is a fragmentary vertical section on the line 4—4 of Fig. 2; and

25 Fig. 5 is a fragmentary vertical section on the line 5—5 of Fig. 3.

The tank 6 of the washing machine is preferably a sheet metal tank having an inverted truncated conical bottom formed primarily with a large axial opening that is normally closed by a plate 7, the flange of which is sweated, welded, or otherwise rigidly secured to the tank bottom. This plate 7 forms the bottom member of a pump casting and is formed with an axially depending bearing hub 8. The top plate 9 of the pump casing is of annular form and, as shown, it is rigidly but detachably secured to the bottom plate 7 by screws 10 working with threaded engagement through lugs 11 on said bottom plate.

35 The tank is supported by suitable legs 12 shown as equipped with rollers at their lower ends and at their upper ends rigidly secured in sockets 13 formed at the outer extremities of the arms of a depressed spider bracket 14, which latter, at the axis of the tank, supports a small electric motor 15 set with its shaft 16 vertical. The upper end of 40 the motor shaft 16 is connected by a flexible shaft coupling 17 to the lower end of a short vertical shaft 18, which latter is journaled in the bearing hub 8 and extends upward axially through the pump casing. The shaft 18 has a collar 19 countersunk into the

bottom plate 7 of the pump casing, and just above said collar, it is shown as provided with driving lugs 20.

The pump employed is of the rotary centrifugal type and its blade-equipped rotor 21 has a hub on the upper portion of the shaft 18 and said rotor is notched to afford seats for the driving lugs 20, as best shown in Fig. 5. This causes the pump rotor to rotate with the shaft 18, but permits the same to be lifted off from said shaft when desired. The axial opening of the annular top plate 9 affords an intake passage for the water pump, and in this intake passage is placed a perforated rotary cylindrical strainer 22, the upper edge of which is secured to a head 23, the hub of which is screwed onto the reduced threaded upper end of the shaft 18.

50 The top plate 9 of the pump casing is provided with peripheral discharge ports 9* that increase circumferentially in height and at their discharge ends are connected to the lower ends of a pair of diametrically opposite discharge tubes 24, which latter curve upwardly and terminate in a large discharge neck 25 that is located high above the pump casing but is concentric with the vertically projected axis thereof. Preferably, the lower ends of the discharge tubes 24 are flanged and rigidly but detachably secured 55 to the tops of the discharge ports by machine screws 26.

55 Rotatively mounted within the lower portion of the tank 6 is a sprayer head 27 provided with perforated tubular operating arms 28. This spraying head 27 is formed with a large depending sleeve that is loosely journaled on the discharge neck 25 and is provided at its lower end with an outstanding annular flange 29 that performs several 60 functions presently to be noted. The numeral 30' indicates a flanged retaining ring that has screw-threaded engagement with the large passage of the discharge neck 25 and is thus secured with its flange overlying the flange 29 but normally standing considerably above the latter, as shown in Fig. 4. Preferably, the central portion of the spraying head 27, as well as its arms 28, is perforated on top for the discharge of water substantially as indicated by arrows on Fig. 1, but the outer ends of the said arms are closed. To cause the arms 28 to perform a function additional to that of spraying the water and delivering the same against the 65

dishes, they are formed or provided with oblique blade portions 28^a and which operate as hereinafter more fully described.

At their point of junction, the two water discharge tubes 24 are formed with a bearing sleeve 30 and in this sleeve is journaled an upright shaft section or spindle 31 that is axially aligned with the shaft 18. The lower end of the spindle 31 is connected to the head 23 by a friction clutch, which, as shown and preferred, is of the disc type and is made up of a plurality of discs, certain of which are arranged to rotate with said head 23 and certain of which are secured to the lower end of the spindle 31 for rotation with the latter. This disc clutch is of a well known type and, hence, is indicated as an entirety by the numeral 32. In disc clutches, the alternated discs are, as is well known, arranged to move axially so that they can be pressed together under greater or less friction; and to regulate this friction, I provide a centrifugal governor. As shown, this governor comprises weighted fly-ball-acting bell cranks 33 pivoted to a small collar 34 secured to the spindle 31. The numeral 35 indicates a governor housing that is secured on the head 23 for rotation therewith. By reference to Fig. 1, it will be noted that the lower end of the spindle 31 is made square, so that it may be axially detached from and axially connected to the disc or discs that rotate therewith when the parts are assembled. At its extreme upper end, the spindle 31 has a depressed notch that receives a transverse driving pin 36 carried by the spraying head 27. Thus, said spraying head is normally connected to rotate with the spindle 31 but is capable of vertical movements in respect thereto, such as required to raise the flange 29 into and out of engagement with the flange of the retaining collar 30'.

Rigidly secured on and rising from the top plate 9 of the pump casing are shearing blades or lugs 37, the purpose of which will presently appear.

The pump casing is provided with a tangential drain port that is connected to a drain pipe 38. This drain pipe 38 extends outward from the bottom plate of the pump casing, on a line first below the bottom of the tank and thence upward to a point far above the level of the water or suds y in the tank, and at its faucet end is provided with a valve 39.

The cooperating flanges 29 and 30, under certain conditions hereinafter noted, afford a friction brake for retarding the rotation of the sprayer head 27, and for many conditions, this one friction brake will serve the purpose. However, for other purposes, I prefer to provide an additional centrifugally set brake, which is preferably of the type best shown in Figs. 1 and 4. This sec-

ondary or auxiliary friction brake, as shown, comprises a pair of weighted levers 40 pivoted to lugs 41 carried by the sleeve portion of the sprayer head 27 and operative on brake pins 42 that work radially through the depending portion of the sprayer head 27 and normally run freely or without frictional contact in an annular channel 43 formed on the exterior of the discharge neck 25, (see Fig. 4), by reference to which it will be noted that said brake pins have enlargements that limit their inward movements. Within the tank, any suitable arrangement of trays may be provided, but I have shown two such trays, the lower of which is indicated by the numeral 44 and the upper by the numeral 45.

Operation.

When the machine is to be used for washing dishes placed in the tray substantially as shown in Fig. 1, the faucet 39 should be closed, so that there will be no discharge of water from the tank through the drain pipe 38. The electric motor 15 will run at relatively high speed, say from fifteen hundred to two thousand revolutions per minute, and the rotor 21 of the pump will, of course, be driven at correspondingly high speed, and also the rotary strainer 22 and one or more of the discs of the clutch 32 will be rotated at the same speed. The wash water or suds will be drawn into the pump casing through the rotary strainer 22 and any coarse particles caught in the perforations of said strainer will be disintegrated or torn to pieces by the disintegrator blades or lugs 37, and, moreover, such particles will be thrown outward by a centrifugal force and, hence, there will be no danger of said rotary strainer becoming clogged with garbage or solid matter washed from the dishes. The first action of the rotary pump is to force the water under high pressure upward through the water discharge tubes 24 and neck 25 into the sprayer head 27 and its arms 28, and this upwardly exerted pressure will raise the sprayer head so that its friction flange 29 will be forced against the flange of the retaining collar 30', thereby producing a friction that will very greatly retard the speed of rotation of the sprayer head. Thus, the sprayer head is held for relatively very slow rotation.

Also when the sprayer head is raised as above just indicated, the brake pins 42 will be raised out of the clearance channel 43 and will then be pressed into frictional contact with the upper portion of the discharge neck 25, which latter, it will be remembered, is a non-rotary element. When thus raised, the inner ends of the brake pins 42 frictionally engage the exterior of the discharge neck 25, and the higher the speed of rotation, the greater will be the force exerted by the

weighted levers 40 tending to press said brake pins against said neck. Hence, it is evident that while the water is being forced into the sprayer head and discharged therefrom and against the dishes, the said sprayer head will rotate slowly and will produce the best kind of delivery of water against the dishes. It may be again noted that the notch 36 in the upper end of the spindle 31 permits the sprayer head to rise and fall and cause the same always to be driven with the spindle 31. The speed of rotation of the sprayer head acquired during the dish-washing action will not be quite enough to cause the 10 weighted levers or governor fly ball elements 33 to very tightly press together the discs of the clutch. Otherwise stated, the frictional retarding action above described will be sufficient to prevent the clutch governor from setting the clutch tight enough to cause the sprayer to rotate at high speed.

As I have demonstrated in practice, when the faucet 39 is opened while the motor is in action, the wash water will be discharged 15 out through the drain pipe 38 and the sprayer head will be entirely relieved from the upward pressure of the water. In fact, water will be completely blown or forced from the tank under the centrifugal action 20 of the rotary pump. This discharge of the water through the opened drain pipe, rather than to and through the rotary sprayer, is due largely to the fact that said drain pipe leads from the tangential discharge port of 25 the casing, so that the wash water finds its freest escape out through said drain pipe.

When the sprayer head is relieved from the upward pressure of the water, it drops back 30 to its normal position shown in Figs. 1 and 4, and both frictional brake devices, towit: that afforded by the flanges 29 and 30 and that afforded by the brake pins 42 and weighted levers, will cease to function and 35 will then leave the sprayer head free for rotation at high speed.

When the sprayer head is thus relieved from the friction of the braking device or devices, the friction of the clutch 32 will be sufficient to immediately increase the speed 40 of rotation of said sprayer, and as this speed increases, the weighted levers or fly balls 33 will progressively increase the friction between the discs of the said clutch and then the motor will impart to the sprayer head 45 and its arms a high speed of rotation, towit: a speed that may somewhat closely approach that of the motor but will not be as great as the speed of the motor. When the sprayer is thus rotated at high speed, the beveled portions 28^a of its arms will act as propeller or fan blades and will blow air upwardly at high velocity, thereby quickly drying the washed dishes. Thus, it will be seen 50 that the sprayer designed as above described 55 on the general plan indicated performs two

functions, towit: that of spraying the water and that of blowing air to dry the dishes.

What I claim is:

1. In a dish washing machine, a tank, a rotary sprayer within the tank, a pump receiving water from the tank and delivering the same to said sprayer, a motor with connections for driving said pump, frictional driving means between said pump and sprayer, and means for braking said sprayer proportionately to an increase in speed of said motor. 75

2. In a dish washing machine, a tank, a rotary sprayer within the tank, a pump receiving water from the tank and delivering the same to said sprayer, a motor with connections for driving said pump, frictional driving means between said pump and sprayer, and means operated by the flow of water for braking said sprayer proportionately to an increase in speed of said motor. 80

3. In a dish washing machine, a tank, a rotary sprayer within the tank, a pump receiving water from the tank and delivering the same to said sprayer, a motor with connections for driving said pump, frictional driving means between said pump and sprayer, means for braking said sprayer proportionately to an increase in speed of said motor, and centrifugally operated braking means operating further to decrease the speed of rotation of said sprayer. 90

4. In a dish washing machine, a tank, a rotary sprayer within the tank, a pump receiving water or air from the tank and delivering the same to said sprayer, a motor with connections for driving said pump, frictional driving means between said pump and sprayer, and means for causing said sprayer to rotate at relatively low speed when water is pumped thereto and for causing it to rotate at relatively high speed when air is pumped thereto. 100

5. In a dish washing machine, a tank, a rotary sprayer within the tank, a pump receiving water or air from the tank and delivering the same to said sprayer, a motor with connections for driving said pump, frictional driving means between said pump and sprayer, and means intermediate said pump and sprayer adapted to decrease the speed of said sprayer when water is forced therethrough by said pump and to increase the speed of said sprayer when air is forced therethrough. 110

6. In a dish washing machine, a tank, a combined rotary sprayer and fan-acting blower within the tank, a pump receiving water or air from said tank and delivering the same to said sprayer, a motor with connections for driving said pump, a friction drive connection between said pump and combined sprayer and blower, and braking mechanism operating only when water is pumped, whereby said combined sprayer and 120

blower will be rotated at relatively low speed in the water-pumping and dish-washing action and will be rotated at relatively high speed when said pump is relieved from the water-pumping action.

7. In a dish washing machine, a tank, a combined rotary sprayer and fan-acting blower within the tank and having vertical limited movement therein, a pump receiving water or air from said tank and delivering the same to said sprayer, a motor with connections for driving said pump, a friction drive connection between said pump and combined sprayer and blower, and braking mechanism operated only by the lift of the combined sprayer and blower when water is pumped therethrough, whereby said combined sprayer and blower will be rotated at relatively low speed in water-pumping and dish-washing action and will be rotated at relatively high speed when said pump is relieved from the water-pumping action.

8. In a dish washing machine, the combination with a tank, of a rotary pump therein, the bottom plate of the casing of which forms a depression in the bottom of said tank, said casing having an axial inlet in its top plate in line with the tank bottom proper, a rotary sprayer in said tank above said pump casing, a motor with connections for driving the rotor of said pump, said pump casing having an outlet connected to said sprayer, a screen rotating with said pump rotor and interposed in the pump casing inlet, and a fixed disintegrator in proximity to the exterior wall of said screen.

9. The combination with a washing tank having a centrally apertured bottom and article receiving racks therein, of a pump casing disposed in and closing said central aperture, a rotary pump in said casing disposed below the bottom surface of said tank, a central fluid inlet from said tank to said casing, means for spraying the fluid through

said tank, a screen interposed in the pump 45 casing inlet, and a disintegrator in proximity to said screen, one of said last two parts being movable relatively to the other.

10. The combination with a washing tank having a centrally apertured bottom and article receiving racks therein, of a pump casing disposed in and closing said central aperture, a rotary pump in said casing disposed below the bottom surface of said tank, a central fluid inlet from said tank to said 50 casing, means for spraying the fluid through said tank, a screen rotating with said pump rotor and interposed in the pump casing inlet, and a fixed disintegrator in proximity to the exterior wall of said screen.

11. In a dish washing machine, a tank, a combined rotary sprayer and fan within the tank, a pump receiving water or air from the tank and delivering the same to said sprayer, a motor with connections for driving both said pump and said sprayer, and means for causing said sprayer to rotate at relatively low speed when water is pumped thereto and for causing it to rotate at relatively high speed when air is pumped 70 thereto.

12. In a dish washing machine, a tank having a water space in the lower portion thereof, a rotary spray generator in the lower portion of the tank above said water space having means to direct water in streams upwardly throughout the tank, a pump in the water space, means forming conduits extending upwardly from the pump for supplying water to the spray generator, and a motor for driving said pump and said sprayer, said sprayer being of fan-shape whereby to generate air currents with the streams of water discharged upwardly within the tank.

In testimony whereof I affix my signature.

JAMES J. GIBNEY.
